Inventor

Uriah D. Seltzer.

UNITED STATES PATENT OFFICE.

URIAH D. SELTZER, OF LEBANON, PENNSYLVANIA.

EGG-BEATER.

SPECIFICATION forming part of Letters Patent No. 487,024, dated November 29, 1892.

Application filed March 26, 1892. Serial No. 426,553. (No model.)

To all whom it may concern:

Be it known that I, URIAH D. SELTZER, a citizen of the United States, residing at Lebanon, in the county of Lebanon and State of Pennsylvania, have invented a new and useful Combined Potato and Egg Beater, of which the following is a specification.

My invention relates to a combined potato-masher and egg-beater, and has for its object 10 to provide such a device as shall be simple in operation and cheap to manufacture, and which shall yet be effective in the various uses for which it may be employed.

In the drawings, Figure 1 is a side elevation 15 of my invention assembled for use. Fig. 2 is a vertical sectional view of the same. Fig. 3 is a detail view of one of the cylinders.

Similar letters of reference in the several figures indicate the same parts. 20 Referring to the drawings, A represents the straining-cylinder; B, the ring; C, the plunger; D, the plunger-rod; E, the handle; F, the cross-head, and G a spring for returning the plunger to its normal position after having been forced down against the action of 25 said spring.

The cylinder A, open at both ends, is made, preferably, from perforated sheet metal and has the stiffening band or bead a around the 30 top and another band or bead b around the bottom, the first-mentioned band or bead a forming a projecting flange around said cylinder and provided with notches a', for a purpose to be presently described.

The cylinder A is adapted to be seated in the annular recess d in the ring B and is held in place by the hook-shaped lugs c, which engage the above-mentioned bead a. To fasten the cylinder in place, it is only necessary to 40 slip the lugs through the notches a' and then turn the cylinder to the right or to the left, as the case may be.

Formed integral with the ring B is the cross-head F, through a bearing d' in the center 45 of which slides the reciprocating plunger-rod D, carrying the plunger C on its lower end. Its upper end forms the operating-handle E. The spring G for retaining the plunger normally in position may be either a bow-spring, 50 as shown in the drawings, or it may be a spiral spring coiled around the plunger-rod. In either case one end is attached to a lug e

on the cross-head F and the other to a corresponding lug g on the handle E.

The plunger C has a diameter just slightly 55 smaller than the inside diameter of the cylinder to permit of the reciprocation of the plunger within said cylinder. By making the perforations in the different cylinders of a varying size I accommodate my device to 60 various uses.

The operation is as follows: When it is desired to mash potatoes, they are placed in a bowl and my device is placed down on them, so that some of the potatoes will be inclosed 65 by the cylinder. Then the handle is pushed down, the plunger descends within the cylinder, and forces the inclosed potatoes out through the perforations of said cylinder. My device is then moved to another part of 70 the bowl and the operation repeated until the potatoes are sufficiently desiccated to suit the taste of the operator.

The advantages and utility of my device are apparent. It has a wide range of usefulness, for it may be used as well for an egg-beater, fruit-press, &c., as for a potato-masher. Combined with the efficient manner in which these operations are performed make it a very desirable object for kitchen use. Its 80 simplicity, too, is a feature. Its parts, being few and easy to manufacture, will enable me to make it at a cost within the reach of every one.

In Fig. 3 I have shown a cylinder having 85 smaller perforations than the cylinder illustrated in Figs. 1 and 2. This cylinder is used when employing the device as an egg-beater, mixing cottage-cheese, whipping cream, &c.

It is apparent that the scope of my invention would include any immaterial changes in my construction which I might wish to make—as, for instance, for some purposes I might wish to close up one end of the cylinder A, &c.

Having thus described my invention, I claim as new and desire to secure by Letters Patent—

1. An implement of the class described, comprising the ring B, the yoke F, formed integral therewith, the open-ended cylinder A, detachably secured to said ring, the spring-actuated plunger C, adapted to reciprocate within said cylinder, the handle E, and lugs g 95 100 105

e, cast, respectively, upon the yoke *F* and handle *E* for retaining the spring *G* in position, substantially as described.

2. An implement of the class described, 5 comprising the ring *B*, having lugs *c* thereon, the cylinder *A*, detachably secured to said ring and provided with the flange or bead *a*, with notches *a'* therein, the yoke *F*, formed integral with said ring *B*, the spring-actuated 10 plunger *C*, adapted to reciprocate within said cylinder, the plunger-rod *D*, attached to said plunger, and the handle *E* for operating said device, substantially as described.

3. An implement of the class described, 15 comprising the ring *B*, the cylinder detachably secured thereto, the cross-head or yoke

F, formed integral with said ring, the plunger *C*, adapted to reciprocate within said cylinder, the plunger-rod *D*, operating-handle *E*, and spring *G*, formed of a single piece of wire 20 looped in the middle, as shown, and having the straight arms attached the one to the handle *E*, the other to the cross-head or yoke *F*, substantially as described.

In testimony that I claim the foregoing as 25 my own I have hereto affixed my signature in the presence of two witnesses.

URIAH D. SELTZER.
